(57) **CLAIM**

The ornamental design for an inflatable floating bed, as shown and described.

DESCRIPTION

FIG. 1 is a top perspective view of an inflatable floating bed, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dot-dash broken line showing of the inflatable floating bed is for the purpose of illustrating portions of the article that forms no part of the claimed design. The evenly broken line showing is stitching and forms no part of the claimed design.

1 Claim, 8 Drawing Sheets
